COMBINATION CORN HUSKING DEVICE

John Robert Kitchel, Fountain City, Ind.

Application March 2, 1936, Serial No. 66,669

3 Claims. (Cl. 130—4)

This invention relates to corn husking devices and in more particular to devices supplementing husking hooks.

An object of this invention is to provide devices 5 to aid in the rapid and thorough manual removal of husks from corn.

Another object of this invention is to provide a husk stripping device to clean the husk from the corn.

10 Another object of this invention is to provide husking devices that are cheap, efficient, easily manipulated and durable.

Another object of this invention is to provide 15 a device that is easily operated, requiring less effort, thereby saving the husker's strength.

Another object of this invention is to provide a device wherein only two operations are required in husking corn, thereby speeding up the work on the farm.

20 With the above primary and other incidental objects in view, as will more fully appear in the specification, the invention consists of the features of construction, the parts and combinations thereof, and the mode of operation, or 25 their equivalents, as hereinafter described and set forth in the claims.

In the drawing, Fig. 1 is a perspective view of the husking hook and the stripping peg as applied to one hand.

30 Fig. 2 is a perspective view of a husk stripping device mounted upon the other hand.

Fig. 3 is a perspective view of an ear of corn 35 grasped by one hand having the husk removed by the other.

Fig. 4 is a fragmentary sectional view taken substantially on the line 4—4 of Fig. 5.

Fig. 5 is another perspective view of the hook and stripping peg as used when the ear hangs downwardly.

40 Fig. 4 has been drawn to a larger scale than that used in Figs. 1, 2 and 3.

In the modifications shown in the drawing and in the description thereof that follows, the husking hook and the stripping peg have been attached to the right hand and the stripping device attached to the left hand, the natural attachment of these devices for a right handed person. For a left handed person the husking hook and peg will, of course, be attached to the 45 left hand and the husk stripping device mounted upon the right hand.

Various types of hooks are used by corn pickers, that are attached to the right hand for removing the husk from one side of the ear of corn, 50 the corn picker stripping the balance of the

husk by the left hand, leaving the ear free to be grasped by the right hand, which gives it a snap to break the ear from the shank. If the husk is heavy or if the corn picker doesn't happen to manipulate his hook properly, some of the husks are left on the ear, which prevents the left hand from removing all of the husks. Husks left on ears are objectionable. Even though all the husks may be removed from one side of the ear by the hook, the corn picker's 5 left hand usually wearing a canvas mitten, may fail to remove all of the husks, thereby leaving 10 some of the husks on the ear.

In the present embodiment a husk stripping peg is mounted adjacent to the hook, which gives 15 a stripping action to strip any residual husks that may be left by the hook. This insures cleaner corn, free of husks. In order to aid the left hand in removing the husks, a stripping member carried in the palm of the hand, having 20 stripping teeth overlying the thumb, aids in the complete removal of all of the husks by the left hand. The tooth arrangement of this member will strip the fine silk-like husks found next to the kernels, even though this husk may have a 25 tendency to stick to the ear.

A flexible member 10 strapped around the hand of the corn picker is provided with a strap 12 that is passed around the thumb. Similar arrangement is used on several types of corn 30 picking hooks. The flexible member 10 has attached thereto a metallic plate 14, that is shaped to fit over the base of the thumb and is provided with a portion 16 extending over the proximal phalanx of the thumb terminating in a hook in 35 the proximity of the distal phalanx joint of the thumb. This hook 18 is mounted adjacent to a husk stripping peg 20 and are joined before the curvature 22 merges into the substantially flat portion 16. Portion 16 may be either integral 40 with, welded to or secured in position by suitable screws or rivets. In the modification disclosed in Fig. 1, 16 has been welded to the plate 14.

In order to provide a solid support and close fit for the plate 14 a suitable pad 24 is preferably 45 inserted under the flexible member 10 so as to be seated in the pit of the palm of the hand. This uniform support for the plate 14 relieves the strain upon the wrist of the corn picker, thereby easing the operation.

As the corn picker advances the hook 18 into the husk, the stripper 20 removes the residual husks, in that 20 follows the hook 18. The hook 18 travels in advance of the stripper or peg 20, 50 as the corn picker draws his hand towards him- 55

self during the first operation of removing the husks from the ear.

After the right hand has removed the husks from one side of the ear, the corn picker usually grasps the remaining husks by the left hand, leaving the right hand free to break the ear from the shank. In the preferred modification, the left hand supports a flexible member 39, similar to the flexible member 10, strapped to the hand in like manner. This member 39 supports a metal plate 32, overlying the base of the thumb and terminating in a plurality of stripping hooks 34. The number of hooks or teeth may vary, depending upon the demands of the individual using the devices and upon the type of corn that is husked. The husk stripping hooks 34 aid the left hand in removing the balance of the husks from the ear, so that as the ear is broken from the shank none of the husks adhere thereto.

Many corn huskers or pickers when using the prior art devices, due to their shape and location of the husking hook or peg, find it necessary to orient the ear into a predetermined angular relation with respect to the position of the husker before proceeding with the husking operations.

The hook 18 and peg 29 permit the rapid husking of corn by two operations of the right hand whether the ear points upwardly as shown in Fig. 3 or downwardly as shown in Fig. 5. In either event the right hand first strips the husk along one side of the ear followed by a second movement when the ear is grasped by the right hand, probably given a slight twist and thrown into the husking wagon or pile. During these operations with the right hand, the left hand holds the ear and strips the husk by the hooks or teeth 34. Thus, it may be seen, that applicant's device expedites the work enabling the users thereof to acquire great speed and efficiency.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the

means and construction herein disclosed comprise the preferred form of several modes of putting the invention into effect, and the invention is therefore claimed in any of its forms or modifications within the legitimate and valid scope 5 of the appended claims.

Having thus described my invention, I claim:

1. A corn husking device including a flexible member fitting the hand, and corn husking means carried by said flexible member, said means 10 including a base plate having integral therewith a unitary curved portion supported in the proximity to the distal phalange joint of the thumb and terminating in a hook portion for removing the outer portion of the husk from one side of 15 the ear, said curved portion supporting a second hook merging into the first hook in spaced relation with respect to the flexible member and having a lesser degree of curvature than the first mentioned hook, said second hook stripping 20 the residual husk from the same side of the ear, said hooks pointing away from the end of the thumb.

2. A corn husking device including a flexible member fitting the hand and a metallic plate 25 member overlying the base of the thumb and merging into an outwardly projecting curved portion terminating in a husking hook pointing away from the end of the thumb, said curved portion also merging into an outwardly projecting husk 30 stripping hook located towards the inside of the hand, said husk stripping hook being substantially normal to the underlying portion of the thumb and connected to the bight of the first hook, the first hook removing the bulk of the 35 husk on one side of the ear, the husk stripping hook removing any residual husk on said side of the ear.

3. A corn husking device including a flexible member fitting the hand, and a metallic plate 40 member overlying a portion of the hand and merging into an outwardly extending curved portion merging a substantial distance out from the surface of the hand into a pair of husk removing hooks, one of which has a greater degree of 45 curvature than the other, so as to progressively engage the husk, the one having the greater degree of curvature engaging the husk first as to remove the greater portion of the husk, any residual husk being removed by said other 50 hook.

JOHN ROBERT KITCHEL.
